SELF-BALLASTED ARC LAMP

George S. Sperti, Fort Mitchell, Ky., assignor to
Institutum Divi Thomae Foundation, Inc.,
Cincinnati, Ohio, a corporation of Ohio

Application May 5, 1941, Serial No. 391,884

4 Claims. (Cl. 176—1)

My invention relates to lamps of a type in which an arc is struck between electrodes in an envelope containing rarefied and ionized gas. Such lamps are useful for a wide variety of purposes. For example, when the envelope contains mercury and is pervious to the shorter wavelengths of light, such lamps are useful as sources of ultra-violet radiations. Employed in connection with fluorescent substances, the lamps are useful as illuminants. The field of utility of the lamps, the nature of the arc (whether low pressure or high pressure), the nature of the substance controlling the wavelength of the radiation, and whether the envelope is pervious or impervious to ultra-violet light or has a filtering action on the light produced do not constitute a limitation on my invention, and will not herein-after be discussed.

The chief object of my invention is the solution of the problem of providing a self-ballasted lamp of the general character referred to above. The problem itself is not new. There has been a need for an arc device which did not require external ballasting impedances such as resistances, chokes or transformers, nor external starting devices. An exemplar of an ideal structure would be a lamp of the type referred to, generally resembling an ordinary incandescent lamp, and capable of the same indiscriminate use in any outlet of the required voltage. I shall describe my invention in an embodiment of this kind, it being understood, however, that the shape of the envelope, the disposition of the parts, the nature of the base and the like may all be widely varied to provide lamps for different fields of use without departing from the invention as expressed in the appended claims.

Much work has been done on self-ballasted lamps and workable structures have been produced. But such structures have had certain defects, the elimination of which form ancillary objects of this invention. Such structures have in general been complicated in form, expensive to produce, frequently fragile and of limited life, and have often involved dual use of elements with accelerated destruction thereof, e. g., the use of filaments both as incandescent elements and as arc electrodes. Moreover the exigencies of the design and manufacture of such devices has frequently been such that the electrode elements could not be properly placed to give an arc of the required length or at a position in the envelope suitable for optimum radiation of the emitted light.

It is also an object of my invention to provide

a self-ballasted lamp which operates in a new way, the advantages of which will appear from the ensuing description.

These and other objects of my invention which will be pointed out hereinafter or will be apparent to one skilled in the art upon reading this specification, I accomplish by that certain combination of elements of which I shall now describe the aforesaid exemplary embodiment. Reference is made to the drawing forming a part hereof and in which:

Figure 1 is a vertical sectional view of the exemplary lamp.

Figs. 2 and 3 are diagrams showing the operation of the device on different cycles of alternating current.

Fig. 4 is a perspective view of the third electrode assembly.

Briefly, in the practice of my invention I provide, in an envelope with a suitable atmosphere, a pair of alternate electrodes, which I will refer to as electrodes A and B. These electrodes are each connected directly to one of the line terminals. Across the line terminals I also provide a double impedance, conveniently a resistance in the form of a filament or filaments. The impedance is double in the sense that not more than substantially half of it is required to ballast the arc. Substantially at the effective mid-impedance point of this element I provide an electrode C, equipped with electron emitting means. These elements, together with supporting means for the parts and shielding means for the filaments, where required, constitute the fundamental operating elements of my structure. Their mode of coaction will be set forth herein-after.

In the exemplary structure shown in Fig. 1, I is an envelope of suitable translucent substance and containing the desired atmosphere under the desired pressure. 2 and 3 are the line terminals passing through a press 4 into the envelope. A pair of alternate arc electrodes A and B are connected to the line terminals. The press is also shown as supporting refractory shielding tubes 5 and 6 of glass, ceramic, quartz or the like. The impedance mentioned above is shown as a continuous filament 7 disposed in substantial U shape, and having its legs encased in and shielded by the tubes 5 and 6. The ends of the filament are connected respectively to the line terminals 2 and 3 as at 8 and 10.

Intermediate the ends of the filament, and preferably at or near the center of resistance I provide an electrode C. There should be an

electron emissive substance in connection with this electrode; and the form of the structure which I prefer to use is shown in Fig. 4. In practice I provide a ceramic block 11 perforated longitudinally as shown. The filament 7 is associated with the block by being laced forwardly and backwardly through the holes, also as shown, so that the passage of current through the filament will heat the block and in turn a metallic sleeve 12 on it. The sleeve 12 is coated with an electron emissive substance such as a refractory oxide. The sleeve is connected to the filament 7 at or near its mid-impedance point by a connection 13. The electrode may be supported from one of the tubes 5 or 7 by a bar 14 or in some other suitable way. Other electrode structures for the electrode C may be employed; but it should be with this electrode that the electron-emissive substance is associated, for reasons which will be clear hereinafter.

The manner of operation of the device is shown in Figs. 2 and 3. The filament heats the electrode C causing the electron-emissive substance associated with it to give off electrons. While the electrode C is located approximately at the mid-impedance point of the filament 7, it will nevertheless (as shown in Fig. 2) be negative with respect to electrode A on one alternation of an alternating exciting current. Under these circumstances an arc will strike between electrode C and electrode A. The portion of the filament lying between C and B will act as ballast for the arc so struck, and the other portion of the filament will be effectively short circuited by the arc. It is true that under these circumstances electrode C will be positive with respect to electrode B; but no arc will be struck between these two electrodes, for the reason that the stream of electrons causes the arc to pass between electrode C and the electrode which is electro-positive with respect to it. On the other half of the alternating cycle, the conditions are reversed, and, as shown in Fig. 3 the arc will pass between electrode C and electrode B which is now electro-positive with respect to it. The portion of the filament lying between A and C will act as ballast for the arc. This alternating action will continue, changing with alternations of the current. First one section of the filament and then the other will act as ballast for the arc, and this is why I have referred to the impedance 7 as a double impedance.

My lamp is, however, operable on direct current as will be clear. After the atmosphere in the envelope has become sufficiently ionized, the arc will strike and pass continuously from electrode C to either electrode A or electrode B depending upon which is electro-positive with respect to C, and this in turn will depend on the way in which leads 2 and 3 are connected to the power terminals.

The tubes 5 and 6 protect the filament sections

and prevent the striking of an arc to any portion of the filament. It will be understood that the lamp will be provided with a suitable base, not shown; and that the placement and disposition of the parts can be varied without departing from the spirit of my invention.

Having thus described my invention, what I claim as new and desire to secure by Letters Patent, is:

- 10 1. In a light source of the character described, an envelope, a press in said envelope, a pair of conductors passing through said press, elongated insulative tubing means engaged with and supported by said press and extending a substantial distance therefrom, a pair of filamentary resistance means connected to said lead-in wires and extending the length of said tubing means, said resistances being connected together beyond the termination of said tubing means and connected 15 to a thermionic cathode, and a pair of electrodes located adjacent said press and connected respectively with said lead-in wires, each of said resistance means having sufficient resistivity to ballast an arc struck between said thermionic cathode and one of said electrodes.
- 20 2. The structure claimed in claim 1 wherein said insulative tubing means consists of two interspaced tubes of translucent substance, each containing one of said resistance means, and in 25 which said thermionic cathode means is supported by one of said tubes.
- 30 3. The structure claimed in claim 1 wherein said insulative tubing means consists of two interspaced tubes of translucent substance, each containing one of said resistance means, and in 35 which said thermionic cathode means is supported by one of said tubes, and in which said thermionic cathode means comprises a metal sleeve coated with electron emissive substance, said resistance means comprising in effect a continuous 40 resistive filament, a portion of which is so located with respect to said sleeve as to heat it, there being an electrical connection between said sleeve and said filament.
- 45 4. The structure claimed in claim 1 wherein said insulative tubing means consists of two interspaced tubes of translucent substance, each containing one of said resistance means, and in 50 which said thermionic cathode means is supported by one of said tubes, and in which said thermionic cathode means comprises a metal sleeve coated with electron emissive substance, said resistance means comprising in effect a continuous resistive filament, a portion of which is so located with respect to said sleeve as to heat it, there being an electrical connection between said sleeve and said filament, and in which said electrodes are supported on wires passing through said press, there being electrical connections between said wires and said lead-in wires.

GEORGE S. SPERTI.
